(57) **CLAIM**

The ornamental design for a wind tunnel portion, as shown and described.

DESCRIPTION

FIG. 1 is a top perspective view of a wind tunnel portion according to our new design;

FIG. 2 is a bottom perspective view thereof;

FIG. 3 is a front view thereof;

FIG. 4 is a back view thereof;

FIG. 5 is a top view thereof;

FIG. 6 is a bottom view thereof;

FIG. 7 is a right side view thereof; and,

FIG. 8 is a left side view thereof.

The broken lines represent unclaimed parts of the wind tunnel portion and form no part of the claimed design.
